US00D830034S

(12) **United States Design Patent** (10) Patent No.: **US D830,034 S**
(45) Date of Patent: ** Oct. 2, 2018

(54) **ECO SCATTERING URN**

(71) Applicant: **Element Urns, LLC**, Greenwood Village, CO (US)

(72) Inventor: **Michael J. Walas**, Irvine, CA (US)

(73) Assignee: **Element Urns, LLC**, Greenwood Village, CO (US)

(**) Term: **15 Years**

(21) Appl. No.: **29/599,339**

(22) Filed: **Apr. 2, 2017**

(51) LOC (11) Cl. **99-01**

(52) U.S. Cl. **D99/5**
USPC **D99/5**

(58) **Field of Classification Search**

USPC D99/5; 27/1, 2; D9/629, 433, 420, 505,
D9/504, 549, 315, 428, 454, 529;

(57) **CLAIM**

The ornamental design for an eco scattering urn, as shown and described.

DESCRIPTION

FIG. 1 is an isometric view of an eco scattering urn showing my new design;
FIG. 2 is a front view thereof;
FIG. 3 is a rear view thereof;
FIG. 4 is a side view thereof;
FIG. 5 is a side view thereof;
FIG. 6 is a top view thereof;
FIG. 7 is a bottom view thereof;
FIG. 8 is an isometric view disassembled;
FIG. 9 is top disassembled views;
FIG. 10 is an isometric view;
FIG. 11 is a front view thereof;
FIG. 12 is arear view thereof;
FIG. 13 is a side view thereof;
FIG. 14 is a side view thereof;
FIG. 15 is a top plan view thereof;
FIG. 16 is a bottom plan view thereof;
FIG. 17 is an isometric disassembled view.
FIG. 18 are top disassembled views;
FIG. 19 is an isometric view thereof;
FIG. 20 is a front view thereof;
FIG. 21 is a rear view thereof;
FIG. 22 is a side view thereof;
FIG. 23 is a side view thereof;
FIG. 24 is a top view thereof;
FIG. 25 is a bottom plan view thereof;
FIG. 26 is an isometric view thereof;
FIG. 27 are top disassembled views;
FIG. 28 is an isometric view thereof;
FIG. 29 is a front view thereof;
FIG. 30 is a rear view thereof;
FIG. 31 is a side view thereof;
FIG. 32 is a side view thereof;
FIG. 33 is a top view thereof;
FIG. 34 is a bottom view thereof;
FIG. 35 is an isometric view thereof; and,
FIG. 36 is top disassembled views.
